OIL BURNER

Thomas I. Krauska, St. Louis, Mo.

Application March 4, 1942, Serial No. 433,356

3 Claims. (Cl. 158—91)

This invention relates to oil burners, and more particularly to oil burners especially designed for use in connection with hot water heating plants, stoves or the like.

An important object of the invention is to provide an oil burner of this character, constructed so that the oil will be completely vaporized on entering the fire-pot, to the end that the maximum amount of heat will be insured, from a given quantity of oil, and at the same time providing a structure which will effectively operate when an inferior grade of fuel oil is used.

Another object of the invention is to provide an oil burner including a baffle or deflector adapted to direct the heat from the burning gases, downwardly into the fire-pot, maintaining the fire-pot of the burner hot, to insure the proper combustion of the fuel entering the burner.

Still another object of the invention is to provide a deflector directly above the fire-pot, which may be tilted laterally to facilitate the lighting of the fuel within the fire-pot, in starting the burner.

With the foregoing and other objects in view which will appear as the description proceeds, the invention consists of certain novel details of construction and combinations of parts herein-after more fully described and pointed out in the claims, it being understood that changes may be made in the construction and arrangement of parts without departing from the spirit of the invention as claimed.

Referring to the drawings

Figure 1 is a plan view of an oil burner, constructed in accordance with the invention.

Figure 2 is a vertical sectional view taken on line 2—2 of Figure 1.

Figure 3 is a sectional view taken on line 3—3 of Figure 1.

Figure 4 is a fragmental sectional view, illustrating a modified form of the invention.

Figure 5 is a plan view of a further modified form of the invention, wherein the burner is of the circular type.

Figure 6 is an elevational view partly in section, illustrating the bell-shaped deflector as provided with a hingedly mounted cover.

Referring to the drawings in detail, the body portion of the burner is indicated generally by 50 the reference character 5, and as shown in this particular form, the body portion is rectangular in shape.

Extending inwardly from the side walls of the body portion, are horizontal flanges 6 that are

disposed in a horizontal line with the bottom of the fire door 7.

At the front and rear ends of the body portion, and connected with the horizontal flanges 6, are inwardly extended flanges 8 which cooperate with the flanges 6 in providing a supporting frame for the fire-pot 9. The fire-pot 9 is of a length slightly less than the length of the body portion 5, providing air spaces at the ends of the fire-pot. The end walls of the fire-pot are provided with rows of openings 10, while the main portion of the fire-pot is solid, with the exception of rows of openings 11 arranged adjacent to the upper edges of the fire-pot, as clearly shown by Fig. 3 of the drawings.

A fuel pipe indicated at 12 extends into the bottom of the fire-pot 9, at a point substantially intermediate the ends of the fire-pot.

The reference character 13 indicates the baffle which normally closes the upper portion of the fire-pot, the baffle being substantially bell-like in formation, the flared end thereof being supported within the fire-pot, as clearly shown by Fig. 3 of the drawings.

Bearings are formed in the end walls of the baffle, and accommodate the shaft 14 to which the baffle is secured, so that movement of the shaft will result in a relative rotary movement of the baffle to expose a portion of the fire-pot for lighting purposes.

A plate indicated at 15 is secured to the upper surface of the baffle, and is of a length to extend throughout the length of the baffle, the width of the plate being greater than the width of the baffle, providing wide extensions 16 overlying the curved sides of the baffle, in spaced relation therewith, providing passageways.

Pins 17 extend laterally from one edge of the baffle, and are designed to normally rest on the horizontal flange 6, at the front of the body portion. At the rear edge of the baffle, the space 18 is provided, since the baffle is of a width less than the width of the open side of the fire-pot 9. The pins 17 normally support the baffle against rotary movement in one direction, but permit the baffle to rotate in a rearward direction. It will of course be understood that the rearward rotation of the baffle is restricted by one edge of the plate 15, which will contact with the horizontal plate 6 extending along the rear wall of the burner. A handle indicated at 19 is formed on one end of the shaft 14, and affords means whereby the baffle may be rotated or adjusted.

In the form of the invention as shown by Fig. 4 of the drawings, the principle of the invention is

carried out in the use of a substantially bell-shaped baffle indicated at 20. In this form of the invention, the baffle is hingedly connected to one wall of the body portion 21, as at 22. In Fig. 5 of the drawings, the body portion of the burner is indicated by the reference character 23, and in this form of the invention, the body portion is circular. A circular flange at 24 extends inwardly from the wall of the body portion and provides a support for the fire-pot 25. The bell-shaped baffle 26 is supported directly over the fire-pot 25 in the same relation with the fire-pot as the baffle shown by Fig. 3 of the drawings.

The baffle 26 is supported on the shaft 27 mounted in suitable bearings within the fire-pot, 15 the shaft being formed with a handle 28 for operating the shaft and baffle secured thereto.

A slightly different form of the invention is shown by Fig. 6 of the drawings. In this showing, the baffle is indicated by the reference character 29, and is provided with a hinged cover 30 that is hingedly connected to one of the plates 31, which are secured to the baffle. When lighting this form of burner, the closure is swung upwardly, permitting easy access to a small quantity of oil which may be fed to the fire-pot directly thereunder, for the initial heating of the fire-pot.

In the operation of the burner, a small quantity of fuel oil is fed into the fire-pot, and the bell-shaped baffle is tilted or moved, to expose a portion of the fire-pot, so that the fuel may be ignited for the initial heating of the fire-pot. When the fire-pot becomes heated to a degree to insure combustion, the baffle is moved to its normal operating position, or to the full line position shown by Fig. 3 of the drawings. As the oil continues to flow into the fire-pot and is burned, the products of combustion are directed downwardly by the bell-shaped deflector, from where they pass upwardly between the edge of the bell-shaped deflector and the body portion, to the smoke-stack not shown, and which forms a part of the usual hot water boiler or furnace.

From the foregoing it will be seen that due to this construction, the vapors are forced or drawn through narrow channels and then mixed with air at the point of combustion, insuring perfect combustion of the lowest grade of fuel oil.

What is claimed is:

1. In an oil burner, a rectangular body portion, 50

having side and end walls a fire-pot mounted within the body portion, said fire-pot having an open top and a curved wall forming the bottom and sides of the pot, a substantially bell-shaped baffle mounted within the body portion, the open side of the baffle being disposed within the fire-pot in spaced relation with the curved wall thereof, providing an annular passageway between the fire-pot and baffle, a shaft extending through the body end walls on which said baffle is rotatably mounted, said fire-pot having a plurality of openings formed therein and through which air enters the fire-pot, and a pipe extending into the bottom of the fire-pot and through which fuel is fed to the fire-pot.

2. In an oil burner, a rectangular body portion, a fire-pot mounted within the body portion, said fire-pot having an open top, and a curved wall forming the bottom and sides of the pot a substantially bell-shaped baffle mounted within the body portion, the open side of the baffle being disposed within the fire-pot in spaced relation with the curved wall thereof, providing an annular passageway, a shaft on which said baffle is mounted, elongated extensions extending beyond the outer surface of said baffle at opposite sides thereof and in spaced relation with the side walls of the body portion, and adapted to direct products of combustion laterally, and a handle on one end of the shaft whereby the shaft may be rotated, and a pipe through which fuel is fed to the fire-pot.

3. In an oil burner, a rectangular body portion having vertical side walls, a fire-pot mounted within the body portion, said fire-pot having a curved wall forming the bottom and sides of the pot, said fire-pot having a plurality of openings formed therein adjacent to the upper edge thereof, a substantially bell-shaped baffle pivotally mounted within the body portion, the open side thereof being disposed within the fire-pot in spaced relation with the curved wall thereof, providing an annular restricted passageway between the baffle and fire-pot, means for directing fuel oil to the fire-pot, and deflector extensions extending laterally from the opposite sides of the bell-shaped baffle and adapted to direct products of combustion laterally towards the side walls of the body portion.

THOMAS I. KRAUSKA.
